UNITED STATES PATENT OFFICE.

PAULDING FARNHAM, OF NEW YORK, N. Y., ASSIGNOR TO TIFFANY & CO.,
OF SAME PLACE.

DESIGN FOR A SPOON, &c.

SPECIFICATION forming part of Design No. 21,988, dated November 15, 1892.

Application filed September 27, 1892. Serial No. 447,064. Term of patent 14 years.

To all whom it may concern:

Be it known that I, PAULDING FARNHAM, a citizen of the United States, and a resident of the city of New York, N. Y., have invented a new and original Design for Spoons, &c., of which the following is a specification, reference being had to the accompanying drawings, which form a part of the same.

This invention relates to a design to be imparted to or worked upon spoons, &c.; and it consists in the novel configuration and ornamentation herein specifically shown and claimed.

Figure 1 of the accompanying drawings is a front view of a spoon with my design applied thereto, and Fig. 2 is a rear view of the same.

My design is mainly worked upon and imparted to the handle of the spoon, &c., although a portion of the design extends over the body of the article. The outline of the edges of the handle is composed of an undulating curved line broken occasionally to correspond with the design on the front and back faces of the handle. The front and back faces of the handle are ornamented with figures in relief.

My design is composed of two parts, the front A, (shown in Fig. 1,) and the back B, (shown in Fig. 2.)

The front part A is traversed along each side by a stemwork undulating in outline. The upper end of the handle is decorated by a somewhat-scallop-shaped ornament, below which is an ornament resembling a festoon of flowers and leaves. Throughout the upper portion of the handle there is a continuation near the edges of the scalloped appearance extending down to a point not far from the

middle of the handle, such scalloped ornamentation being varied by bunches of flower and leaf forms and by scroll ends to the side stems. Conventionalized leaf and flower forms are grouped near the middle of the handle. The lower part of the handle is mainly ornamented by conventionalized leaf forms, but also contains a bunch of flower and leaf forms.

The back part B is traversed along each side by a stemwork undulating in outline. The upper end of the handle is decorated by a somewhat-scallop-shaped ornament and contains a few leaf forms. Throughout the upper portion of the handle there is a continuation near the edges of the scalloped appearance extending down to a point not far from the middle of the handle, such scalloped ornamentation being varied by bunches of flower and leaf forms and by scroll ends to the said stems. The lower part of the handle contains conventionalized leaf forms and a group of leaf and flower forms, while below this, extending over the bowl of the spoon, is a somewhat-scallop-shaped ornamentation.

What I claim, and desire to secure by Letters Patent, is—

1. In the design for spoons, &c., the front A, substantially as shown.
2. In the design for spoons, &c., the back B, substantially as shown.
3. The design for spoons, &c., consisting of the front A and the back B, substantially as shown.

PAULDING FARNHAM.
